UNITED STATES PATENT OFFICE.

HENRY A. HEMPEL, OF BUFFALO, NEW YORK.

PRINTER'S QUOIN.

No. 866,358.

Specification of Letters Patent.

Patented Sept. 17, 1907.

Application filed June 10, 1907. Serial No. 378,123.

To all whom it may concern:

Be it known that I, HENRY A. HEMPEL, a citizen of the United States, residing at Buffalo, in the county of Erie and State of New York, have invented a new and 5 useful Improvement in Printers' Quoins, of which the following is a specification.

This invention relates to printers' quoins of the class consisting of a metallic wedge adapted to bear with its inclined face against the corresponding face of a companion quoin, the opposing quoins of a pair having gear racks with which a pinion-key is engaged for moving the quoins lengthwise on each other to tighten or release them.

The invention has particular reference to quoins of 15 this kind which are provided with locking means for preventing the same from working loose or slipping on each other by the jarring of the printing press, especially when it is run at a high speed or when a form is required to be used in the press for an unusually long 20 time.

The object of my invention is to provide such quoins with a reliable locking device which is inexpensive in construction and which in no way interferes with their ordinary use.

25 In the accompanying drawings: Figure 1 is a side elevation of a pair of quoins embodying one form of the invention. Fig. 2 is a face view of one of the quoins. Fig. 3 is a longitudinal section in line 3—3, Fig. 1. Fig. 4 is a transverse section in line 4—4, Fig. 3. Fig. 5 is a 30 fragmentary longitudinal section in line 5—5, Fig. 3. Fig. 6 is a view similar to Fig. 3, showing a modified construction of the locking device. Fig. 7 is a transverse section in line 7—7, Fig. 6.

Similar letters of reference indicate corresponding 35 parts throughout the several views.

A and B indicate a pair of quoins each provided on its face or inclined side with a central longitudinal rib c and at its large end with a head or lug D having a central guide-groove d which receives the rib of the companion quoin. As is customary in such quoins the 40 lugs D project beyond the ribs c and the lug of each quoin bears against the inclined face of the opposing quoin. On opposite sides of the ribs c are arranged the usual gear racks f with which the pinion-key, not shown, engages.

The groove d of each quoin is provided in one of its walls with one or more locking teeth, faces or projections d¹ which are adapted to interlock with corresponding teeth, faces or projections c¹ formed on the opposing side of the rib of the companion quoin, as shown in Fig. 3, so as to prevent slipping of the quoins on each other when tightened in a form or chase. The grooves d are considerably wider than the thickness of the ribs c to allow the ribs to move laterally into and out of engagement with the locking teeth d¹, and to receive springs g which tend constantly to press the ribs sidewise into

engagement with said teeth. For this purpose, the spring g of each quoin is arranged adjacent to the smooth or untoothed wall of the groove d, so that the spring is strained or deflected by the rib of the opposing quoin upon moving the quoins lengthwise on each other in the direction in which they are tightened.

In the embodiment of the invention shown in Figs. 1 to 5, inclusive, each spring consists of a tapering blade or strip of spring steel which is driven into an opening h, preferably of cylindrical form, arranged in the large end of the quoin and extending from the back thereof to the face of the lug D. This spring blade extends forwardly beyond the bottom of the groove, preferably flush with the face of the lug D, as shown 70 in Figs. 4 and 5, and this projecting portion of the spring is free to yield, while its rear portion is rigidly held in place by the engagement of its edges with the wall of the opening h.

To facilitate the entrance of the front ends of the 75 ribs between the springs g and the toothed walls of the groove d, said ends are tapered or wedge-shaped and the springs are arranged obliquely or at an angle to the toothed walls, the edges of the springs which face the large ends of the quoins being nearer said walls than 80 their opposite edges, as shown in Fig. 3.

To obtain the best results, the locking projections d¹ of each quoin are preferably in the form of ratchet teeth with their abrupt sides facing the large end of the quoin, as shown in the drawings.

85 These locking devices, while permitting the quoins of a pair to be shifted lengthwise on each other in the customary manner for tightening or loosening them, hold the quoins against longitudinal displacement with sufficient security to prevent their slipping on 90 each other under the jars or vibrations of the printing press, thus reliably locking the type in the form or chase.

It is to be noted that the quoins of a pair may be 95 identical in construction, as shown, rendering them interchangeable.

It is only necessary to arrange locking means on that side of each rib which faces the toothed wall of the groove of the companion quoin, but if desired, both sides of the rib may be toothed, as shown in the drawings.

If desired, other forms of springs or yielding holding devices may be employed for forcing the toothed rib of each quoin of a pair laterally into engagement with the toothed wall of the groove of the companion quoin. 105 For example, in the modification shown in Figs. 6 and 7, each spring consists of an approximately U-shaped strip of spring steel arranged substantially parallel with the inclined face of the quoin. The shank or outer arm g¹ of the spring is driven into a saw-kerf in the face of the lug D¹, while its inner arm is arranged in the groove of the lug and forms an elastic tongue which 110

bears against the side of the rib of a companion quoin in the same manner as the first-described spring.

I claim as my invention:—

1. The combination of a pair of quoins, one having a longitudinal rib and the other a guide groove adapted to receive said rib, said rib and the wall of said groove having interlocking means, and yielding means arranged to press said rib laterally against said wall, substantially as set forth. 35
- 10 2. The combination of a pair of quoins, one having a longitudinal rib and the other a guide groove adapted to receive said rib, said rib being provided on its side with means constructed to interlock with the opposing wall of said guide-groove, and a spring for pressing said rib laterally against said wall, substantially as set forth. 40
- 15 3. The combination of a pair of quoins, each having a longitudinal rib and a lug having a guide-groove adapted to receive the rib of the other quoin, said ribs being provided on their sides with locking faces and the walls of 45 said groove having similar faces adapted to engage with those of the ribs, and springs arranged in said grooves and acting to press said ribs laterally into engagement with the locking faces of the grooves, substantially as set forth. 50
- 20 4. A quoins provided on its face side with a longitudinal rib and a lug having a groove adapted to receive the rib of an opposing quoins, the rib and a wall of the groove having locking faces, and a spring located in said groove opposite the wall having said locking faces, and arranged to press the rib of an opposing quoins laterally against said wall, 55 substantially as set forth. 60
- 25 5. The combination of a quoins provided on its face side with a longitudinal rib having locking teeth on its side, a lug having a groove adapted to receive the rib of an op-

posing quoins and an opening leading to said groove adjacent to one of its walls, the opposite wall of the groove having locking teeth adapted to interlock with the toothed rib of an opposing quoins, and a spring located in said opening and extending into said groove, and arranged to press the rib of an opposing quoins laterally against said wall, substantially as set forth. 35

6. The combination of a quoins provided on its face side with a longitudinal rib, a lug having a groove adapted to receive the rib of an opposing quoins and a cylindrical opening extending from the back of the quoins into said groove, the rib and one of the walls of said groove having locking faces, and a spring-blade driven into said opening and extending into said groove, substantially as set forth. 40

7. The combination of a quoins provided on its face side with a longitudinal rib, and a lug having a groove adapted to receive the rib of an opposing quoins, one of the walls of said groove having locking faces, and a spring extending into said groove opposite the wall thereof having the locking faces and arranged obliquely to said wall, substantially as set forth. 50

8. The combination of a quoins provided on its face side with a longitudinal rib having a tapering front end and a lug having a groove adapted to receive the rib of an opposing quoins, one of the walls of said groove having locking faces, and a spring extending into said groove opposite the wall thereof having the locking faces and arranged obliquely to said wall, substantially as set forth. 55

Witness my hand this 6th day of June, 1907.

HENRY A. HEMPEL.
